CENTRIFUGAL BOWL

Alan E. Flowers, Poughkeepsie, N. Y., assignor to
 The De Laval Separator Company, New York,
 N. Y., a corporation of New Jersey

Application August 5, 1942, Serial No. 453,611

4 Claims. (Cl. 233—29)

The object of my invention is to provide a centrifugal bowl that is especially adapted to the preparation of blood plasma for use as a substitute for direct transfusion of whole blood. The primary requisite for whole blood transfusion is that the blood of the donor shall be of the same type as that of the patient. It has been found that the characteristics of a donor's blood that prohibit its use with a patient whose blood is of a different type exist in the blood corpuscles, principally red cells, and that, if the removal of these is complete the plasma can be used regardless of the type of blood from which it is prepared. It has been found that such plasma can even be dried, preserved as a powder and, when needed, dissolved in water and injected into the veins of a person suffering from shock or loss of blood.

These facts are well understood. It is also known that the separation of the plasma from the red blood corpuscles can be effected in a centrifugal separator. A most efficient type of separator is one which comprises a bowl provided with "discs", a distributor which the bowl surrounds, and a feed tube or central receiving chamber extending within the distributor and communicating, through the distributor, with the bowl beneath the "liner" of discs therein. It is necessary, in bowls of this type, in order that all surfaces can be cleaned and sterilized to the high degree needed in surgical work, that the bowl should be separable to such an extent that all surfaces that come in contact with the material being treated are accessible for washing, brushing and inspection. Such bowls are known, but their use in the separation of plasma from red blood corpuscles has not been satisfactory. There is always a very slight, but appreciable, contamination of the separated lighter constituent (the plasma) with the red blood corpuscles. In other words the separation is apparently not altogether complete. The degree of such contamination, when the centrifuge is used for most purposes, is so small as to be practically negligible, but such slight degree of contamination is inadmissible in the separation of blood plasma. As above stated, the failure of separators of the type described to give perfect separation has been attributed to an inherent incapacity of any centrifuge to effect a really clean separation.

I have found, however, that this assumption is not warranted so far as concerns those members of the bowl which, in operation, effect the actual separation. The difficulty in preventing

any slight degree of contamination may be explained as follows: In order to cause flow of liquid through the bowl the pressure in the passages for inflow of raw material must be considerably greater than that for the outflowing separated constituents. I have found that the cause of contamination, in a bowl of the type described, is not imperfect separation of the constituents, but a slight leakage, under operative conditions, between certain concentric parts that are unavoidably loose enough to permit their separation for cleaning and inspection. Specifically, I have found this slight leakage to occur between the central feed tube and the distributor and between the upper side of the lower part of the distributor and the under side of the bottom disc. In other words, the perfectly separated lighter constituent is contaminated before it escapes from the bowl, with the incoming liquid to be separated.

In the accompanying drawing, Fig. 1 of which is a vertical section through a separator of the type I have described and Fig. 2 a cross-section on the line 2—2 of Fig. 1, I have illustrated means that effectively seals the joints between these parts, whereby all leakage is prevented. In a separator so constructed, the plasma is separated wholly free of red blood corpuscles. The structural details of the illustrated centrifuge will be described and the novel elements thereof particularly indicated.

A spindle 1 supports and drives the centrifugal bowl. The bowl comprises a combination bottom 2 and central tube or receiving chamber 3; a shell 4 having a neck 24; distributor 5; a plurality of frustro conical members, technically called discs, including a bottom disc 6, a top disc 7 with neck 8, and a plurality of intermediate discs 9 (only two of which are shown) which, with the usual spacers to hold them a short distance apart, fill the space between the bottom and top discs; and a nut 10 which, when screwed onto the upper end of the central tube 3, holds the bowl together.

Projecting down into the center of the bowl is a feed tube 11 with an outlet 12 opening into the receiving chamber 3. An opening 13 through the wall of the central tube or receiving chamber 3 communicates, through a passage 14 along the inside of the distributor 5, with an annular chamber 15, from which a number of outlets 16 lead to an equal number of passages 17 between the bottom disc 6 and the bowl bottom 2. Through the bottom disc, near to its periphery,

distributing holes 18 lead to similar holes 19 in the intermediate discs 9.

On the outside of the distributor 5 there are three or more vertical ribs 20 which centralize and guide the bottom disc 6 and intermediate discs 9. Between these ribs are vertical passages 21 which lead to outlets 22 through the neck 8 of the top disc 7 and in alignment with openings 23 in the neck 24 of the bowl shell 4.

On the top of the top disc 7 there are wings 25 which hold it away from the shell 4, leaving passages 26 that lead to openings 27 through the neck of the bowl shell. 28 is the customary rubber bowl ring that seals the joint between the bowl bottom and the shell.

29 is a resilient compressible ring which seals the space and prevents leaks between the central tube 3 and the distributor 5. 30 is a similar ring that prevents leaks between the larger diameter portion of the distributor 5 and the under side of the bottom disc 6.

In operation, blood fed into the tube 11 is discharged from the outlet 12 to the inside of the tube 3, whence it flows through the opening 13 and passage 14 to the annular chamber 15 which it fills. From this chamber the blood flows through the outlets 16 and passages 17 to the distributing holes 18 and 19, which feed the blood to all the spaces between the discs 9. In these spaces the plasma, which is the lighter constituent, is forced to flow toward the center and then up through the passages 21 and is discharged from the outlets 22 into a receptacle, not shown. The blood corpuscles, which are heavier than the plasma, separate from the plasma while between the discs and move outward to the space between the discs and bowl shell then upward and inward through passages 26 to the openings 27 through which they escape into a receptacle not shown.

I have found that interposing resilient compressible rings between the parts hereinbefore specified will stop all leaks of unseparated blood into the purified plasma and cause perfect work by a bowl that bowl otherwise give results far short of those required to effect a clean separation of the plasma.

While the improved centrifugal bowl is particularly adapted to and intended for the particular use hereinbefore described, it will be found useful, and often highly desirable, in other fields, for example: the separation of colloidal contaminants from liquids in which they are dispersed, such as airplane and Diesel engine lubricating oils, medical preparations, pure chemicals, etc. Obviously, my improved centrifugal bowl, with compressible seals between separable parts, is adapted for general use, since the cleaner separation that it effects is desirable even when not absolutely required.

What I claim and desire to protect by Letters Patent is:

1. In a centrifuge for separating blood plasma suitable for transfusion from other constituents of whole blood, the combination of a central tube enclosing a whole blood receiving chamber; a bowl chamber; said bowl chamber comprising a bowl bottom, a bowl shell having an upper neck provided with an outlet for separated plasma and a tubular member whose upper part fits around the receiving chamber and whose lower part communicates with the receiving chamber and forms a distributor, and a pile of discs within the bowl chamber the lowermost of which rests on the lower part of the distributor and is spaced

from the bowl bottom and provides communication between the distributor and the bowl chamber, and means preventing contamination of the outwardly flowing lighter separated constituent with inflowing liquid to be separated, said means comprising a seal between the contacting walls of the receiving chamber and distributor and a seal between the contacting walls of the distributor and the bottom disc.

2. In a centrifuge for separating blood plasma suitable for transfusion from other constituents of whole blood, the combination of a central tube enclosing a whole blood receiving chamber; a bowl chamber; said bowl chamber comprising a bowl bottom, a bowl shell having an upper neck provided with an outlet for separated plasma and a tubular member whose upper part fits around the receiving chamber and whose lower part communicates with the receiving chamber and forms a distributor, and a pile of discs within the bowl chamber the lowermost of which extends from the lower part of the distributor and is spaced from the bowl bottom and provides communication between the distributor and the bowl chamber, and means insuring against leakage of the inflowing whole blood into separated blood plasma and thus preventing contamination of the latter, said means comprising, a seal, between the contacting walls of the receiving chamber and the tubular distributor, located above the outlet from the receiving chamber to the distributor and preventing flow of whole blood from the receiving chamber except into the distributor, and a tight connection between the lower part of the distributor and the bottom disc preventing flow of whole blood from the distributor except into the bowl chamber.

3. In a centrifuge primarily intended for separating blood plasma suitable for transfusion from other constituents of whole blood, the combination of a bowl comprising a bottom and a shell having a neck, a central receiving chamber extending into the bowl neck, a top disc in the bowl also extending into the bowl neck and spaced from the central receiving chamber to provide an outlet passage for the lighter separated constituent, a removable distributor surrounding, and throughout a substantial part of its height fitting, and communicating with an opening in, the central receiving chamber and forming the inner wall of the bowl and terminating at its top below the discharge from said outlet passage, a bottom disc in, and spaced from the bottom of, the bowl and throughout a substantial part of its area removably fitting against the distributor and the space below which provides communication between the distributor and the separating space enclosed by the bowl, and means preventing contamination of the outwardly flowing lighter separated constituent with inflowing liquid to be separated, said means comprising a seal between the walls of the receiving chamber and distributor where they contact above the outlet from the receiving chamber and another seal between the contacting walls of the distributor and the bottom disc.

4. In a centrifuge primarily intended for separating blood plasma suitable for transfusion from other constituents of whole blood, the combination with a centrifugal bowl having a central tubular element providing a central receiving chamber, a distributor comprising a tubular element which surrounds and is concentric with the receiving chamber and has a close fit thereon but is slidable thereon to facilitate removal for clean-

ing, there being a feed opening in the receiving chamber wall and, communicating therewith, a channel in the lower part of the distributor, a liner in the bowl chamber comprising a pile of discs, the lower end of the distributor being outwardly enlarged and resting upon the bowl bottom and having an upper sloping face adapted to support the bottom disc in such position as to space it from the bowl bottom and thus provide a passage affording communication between the distributor channel and the separating space of the bowl, the separating chamber having an outlet for the lighter separated constituent outside

5 the upper end of the receiving chamber and above the upper end of the distributor chamber, and resilient compressible rings, one between the central receiving chamber and the distributor between the upper and lower ends of their contacting walls, and the other between the bottom disc and the disc-supporting face of the enlarged lower end of the distributor, thereby preventing contamination of the separated outflowing lighter liquid constituent with inflowing liquid to be separated.
